DRAFTING INSTRUMENT

Aaron Waldman, New York, N. Y.

Application December 2, 1943, Serial No. 512,610

2 Claims. (Cl. 33—174)

The present invention relates to new and useful improvements in drafting instruments, and has for its primary object to provide, in a manner as hereinafter set forth, novel means for facilitating the rapid and accurate drawing of radio and other symbols.

Other objects of the invention are to provide a drafting instrument of the aforementioned character which will be simple in construction, strong, durable, compact, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a top plan view of a drafting instrument constructed in accordance with the present invention.

Figure 2 is a fragmentary view in section, taken substantially on the line 2—2 of Figure 1.

Figure 3 is a fragmentary sectional view, taken substantially on the line 3—3 of Figure 1.

Figure 4 is a detail view in plan of one of the slidable coil symbol plates.

Figure 5 is a cross sectional view, taken substantially on the line 5—5 of Figure 1.

Referring now to the drawing in detail, it will be seen that the embodiment of the invention which has been illustrated comprises a triangle 1 of Celluloid or other suitable material, which triangle may be of any desired dimensions.

As illustrated to advantage in Figure 5 of the drawing, the triangle 1 comprises comparatively thin portions 2 providing raised or elevated surfaces on the bottom or lower face of said triangle. The portions 2 of the triangle 1 have formed therein slots and openings, and groups of slots and openings, which conform in shape and arrangement to radio or other symbols, as at 3. The slots or openings 3 are for the reception of a pen or pencil. The triangle 1 is further provided with a plurality of circular openings 4 of different sizes.

In one end portion, the triangle 1 has formed therein elongated openings 5 of uniform width and diameter with which right angularly extending slots 6 communicate at an intermediate point. As best seen in Figure 2 of the drawing, the longitudinal walls of the openings 5 are grooved, as at 7, to slidably receive the longitudinal marginal portions of thin, resilient plates 8 of Celluloid or other suitable material.

The plates 8 have formed therein parallel series of substantially segmental openings 9 with slots 10 therebetween. In one longitudinal edge, the plates 8 are further provided with spaced notches 11. The notches 11 are for the reception of slidable latches 12 which, as illustrated in Figure 3 of the drawing, are dovetailed into the slots 6. Operating lugs 13 are provided on the slidable latches 12. Substantially similar elements 14 are provided on the slidable plates 8.

It is thought that the manner in which the device is used will be readily apparent from a consideration of the foregoing. Briefly, to draw the different symbols, a pen or pencil is inserted 15 through the slots and openings 3. The raised surface portions 2 of the triangle 1 prevent smearing when ink drawings are being made. In the embodiment shown, the symbols 3 are those of a battery, as at 15, a resistor 16, et cetera. The slidable plates 8 with the substantially segmental openings 9 and the slots 10 therein are for making different sizes of radio coil symbols. To draw a coil symbol, the plate 8 which is to be used is locked in one of its positions through the medium 20 of the latch 12 which is engaged in one of the notches 11. An instrument is inserted through the openings 9 and substantially C-shaped segments are drawn. The latch 12 is then retracted, the plate 5 is shifted longitudinally and again 25 locked by engaging the latch 12 in the other notch 11. The operation is then repeated and a line is drawn in the slot 10 with the result that the substantially C-shaped segments which were drawn last overlap and join the ends of those which were first drawn and thus a complete coil symbol 30 is had.

It is believed that the many advantages of a drafting instrument constructed in accordance with the present invention will be readily understood, and although a preferred embodiment of the device is as illustrated and described, it is to be understood that changes in the details of construction and in the combination and arrangement of parts may be resorted to which will fall 35 within the scope of the invention as claimed.

What is claimed is:

1. A drawing instrument comprising a sheet having an elongated opening therein and further having a slot therein communicating with the opening, a plate slidable in the opening, said plate having openings therein for the reception of a drawing instrument, and a latch slidable in the slot and engageable with the plate for releasably securing said plate against sliding movement.
2. A drawing instrument of the character de-

scribed comprising a transparent triangle having an elongated opening therein and further having a slot therein communicating with the opening at an intermediate point, the longitudinal walls of the opening having grooves therein, an elongated

plate slidably mounted in the grooves and having notches in one of its longitudinal edges at spaced points, and a latch slidably mounted in the slot and engageable selectively in the notches for releasably securing the plate against sliding movement in the triangle, said plate having openings therein for the reception of a drawing instrument.

AARON WALDMAN.
